ATTORNEYS.

UNITED STATES PATENT OFFICE.

JOHN B. MEIER, OF PORT HURON, MICHIGAN.

DESIGN FOR A TAPPING-HAMMER.

SPECIFICATION forming part of Design No. 26,638, dated February 16, 1897.

Application filed December 26, 1896. Serial No. 617,102. Term of patent 7 years.

To all whom it may concern:

Be it known that I, JOHN B. MEIER, a citizen of the United States, residing at Port Huron, in the county of St. Clair and State of Michigan, have invented and produced a new and original Design for a Tapping-Hammer; and I do hereby declare the following to be a full, clear, and exact description of the same, reference being had to the accompanying drawings, forming a part thereof.

My invention relates to a design for a tapping-hammer for tapping beer-kegs.

It relates to the entire configuration of the hammer.

My invention relates particularly to a tapping-hammer as illustrated in the accompanying drawings, in which—

Figure 1 is a perspective view of a tapping-hammer embodying my invention. Fig. 2 is a transverse section, and Fig. 3 is a longitudinal section of the same.

In the accompanying drawings the same reference-numerals indicate the same parts of the invention.

The leading features of my design for a

tapping-hammer appear in the following description.

1 represents a tapering cylindrical head, on the larger end of which appears an annular semicircular bead 2, while the smaller end 30 shows an annular right-angular shoulder 3, and a straight portion 4, terminating in a transverse face 5, which forms the hammer-head.

6 represents a radial groove extending longitudinally the entire length of the hammer. The bottom or pocket 6 of this groove is semi-circular, as shown.

Having thus fully described my invention, what I claim as new, and desire to secure by 40 Letters Patent of the United States, is—

The design for a tapping-hammer, substantially as shown and described.

In testimony whereof I affix my signature in presence of two witnesses.

JOHN B. MEIER.
